Primary Examiner — Rosemary K Tarcza*Assistant Examiner* — Christy M Nemeth*(74) Attorney, Agent, or Firm* — Novick, Kim & Lee, PLLC; Allen Xue; Hyun Woo Shin**CLAIM**

We claim the ornamental design for a socket, as shown and described.

DESCRIPTION

FIG. 1 is a bottom, front perspective view of a socket, showing our new design;

FIG. 2 is a top, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show portions of the socket which form no part of the claimed design.
